H. N. H. LUGRIN,

WINDOW SCREEN.

APPLICATION FILED MAY 29, 1917.

1,278,957.

Patented Sept. 17, 1918.

UNITED STATES PATENT OFFICE.

HORATIO N. H. LUGRIN, OF WINTHROP, MASSACHUSETTS.

WINDOW-SCREEN.

1,278,957.

Specification of Letters Patent. Patented Sept. 17, 1918.

Application filed May 29, 1917. Serial No. 173,256.

To all whom it may concern:

Be it known that I, HORATIO N. H. LUGRIN, a citizen of the United States, residing at Winthrop, in the county of Suffolk and

5 State of Massachusetts, have invented certain new and useful Improvements in Window-Screens, of which the following is a specification, reference being had therein to the accompanying drawing.

10 My invention relates to certain improvements in window screens and has for its principal object to provide a new and improved method of screening and curtaining windows, especially windows of bungalows, 15 beach cottages, and other dwellings.

One of the objects of my invention is to provide a screen that can be moved from one room to another to be readily used on other windows and which can be quickly rolled up 20 a sufficient distance to allow of mops, dusters and other articles shaken out of the lower or upper portion of the window.

25 Another object is the providing of a screen of cotton mosquito netting entirely closing the window and so adapted as at all times to fit close to the sides of the window and the top and bottom of window to prevent the entrance of flies and other insects and bugs.

The invention consists in certain novel 30 features of construction and arrangement of parts which will be fully understood by reference to the description of the drawings and to the claims hereinafter given.

35 Of the drawings: Figure 1 represents a front elevation of a window with my device attached, broken away centrally of its width and length in order to more clearly illustrate on a larger scale the details of my invention. Fig. 2 is a sectional view on the line 2—2 of Fig. 1. Fig. 3 is a front elevation of a modified form of part of the invention. Fig. 4 is a side sectional elevation of the modified form shown in Fig. 3.

40 45 Similar characters designate like parts throughout the several figures of the drawings.

Latitude is allowed herein as to details, as they may be changed or varied at will without departing from the spirit of my inven-

tion and the same yet remain intact and be 50 protected.

In the drawings 5 represents the window casing, 6 the window, of which further details is deemed unnecessary. The other characters refer to my invention, of which 55 7 represents a flat oblong board adapted to extend across the top of the window and casing and held in place by any desirable means, as for example, screw eyes 8 adapted to slip over screw hooks 9, the former 60 screwed into the top edge of board and the latter into the casing above the window. This board is preferably curved or beveled on its lower front edge and carries on its under side the bearings 11 in which is 65 mounted the roller 12, for the purposes hereinafter stated.

The board 7 carries on the upper part of its front face a pair of ordinary window curtain brackets 13 in which revolves the 70 curtain roller 14; the roller and its brackets being of the common type used for window curtains, the roller being provided with the spring as is common in such rollers and with the ordinary type of spring lock in one of the 75 brackets 13. This roller 14 carries a screen 15 of common mosquito netting provided with the tape edge 16 and reinforced at its lower edge with a wide strip of linen or cotton cloth or canvas 17 provided across 80 its top with the metal rod 19 and across its lower edge with the ordinary curtain stick 18, as clearly shown in Figs. 1 and 2. If desired the screen 15 may be of copper wire or other material.

85 If desired, the screen may be provided with the common type of curtain tassel or handle to raise and lower the screen and I have preferably shown on the drawings screw eyes 21 screwed into the curtain stick 90 18 adapted to fit upon the screw hooks 22 in the lower side of the window casing beneath the window 6. As some types of locks in the curtain roller brackets only allow the curtain to rest at certain distances I extend 95 the rod 19 and the stick 18 beyond the edges of the tape 16 and provide elastic bands or springs 20 to engage these extended edges

and thus take up any slack in the screen at the sides, so that these sides are brought tight up against the window casing 5.

The board 7 also carries on its front surface at points beneath the brackets 13, a pair of similar brackets 23, but these brackets may be of any other style or type and may have slightly longer arms, as shown in Fig. 2, so that the window shade 25 carried by the roller 24 mounted in the brackets 23, when rolled up will not interfere with the rolling up or down of the screen 15. In Figs. 1 and 2 the window shade 25 is broken away across its lower portion. As clearly shown in these two figures, the screen 15 extends between the bottom of the board 7 and the roller 12, passing by the beveled or curved edge 10 and therefore the screen is held its entire length, from the roller 12 down to the hooks 22 tight against the window casing, and the window 6 is tightly screened. The shade and the screen can be quickly rolled up and the board removed to another window.

In the modified form of the board, shown in Figs. 3 and 4, and which is a cheaper form of board arrangement, I have left off the roller 12 and its bearings 11, but have provided an oblong slot 26 in the lower portion of the board, which is a little wider than the width of the screen. This slot 26 extends through the board 7 downwardly from the front to rear, the edges of the slot being preferably beveled or curved to cause less wear on the screen and prevent breakage and the rear portion of the board 7 beneath the slot is cut away as shown in Fig. 2 to allow the board to be flush against the window casing and yet give sufficient passage way for the screen.

It is to be understood that my invention is not limited to the specific details of construction shown in the accompanying drawings, but that said details may be varied in the practical carrying out of my invention. It is also to be understood that the combinations specifically set forth in the several claims are intended to be separately claimed without limitation to the use in connection therewith of other features and details of construction illustrated.

It is believed that the operation and many advantages of the invention will be thoroughly understood from the foregoing descriptions.

Having thus fully described the nature, construction and operation of my invention, I claim and desire to secure by Letters Patent:—

1. A device for screening windows consisting of a removable board adapted to be hung at the top of a window casing, a roller screen mounted on the board and means for

holding the sides of the screen when unrolled flat against the window casing. 65

2. A device for screening windows consisting of a removable board adapted to be suspended from the upper part of a window casing having a runway and a roller screen mounted on the board and passing rearwardly through the runway against the window casing. 70

3. A device for screening windows consisting of an oblong removable board adapted to be hung on screw hooks in the casing above the window, a window screen, mounted on a rotatable support, a shade mounted on a rotatable support beneath and forward of the screen, and means for firmly securing the screen when unrolled. 75

4. A screening device consisting of a portable board normally suspended on hooks in the upper part of a window casing and instantly removable therefrom, a window shade mounted on its lower portion, a screen mounted on a rotatable support carried by the board above the shade but adapted to pass downward rearward of the shade, and means for passing the screen rearwardly and holding it tight against the upper portion of the window casing. 80

5. A window screen portably mounted on a board, means for holding the screen when in position on a window casing tight against the sides of the casing, means for holding the screen tight across the top of the window casing and means for securing the lower edge of the screen against the lower edge of the window casing. 85

6. A window screen consisting of an oblong board having a runway in its lower portion, a screen mounted on the board and passing downward through the runway having reinforced sides and bottom edge, a curtain stick carried by the reinforced bottom edge, a rod carried by this bottom edge at the upper part of the reinforcement and means for engaging the rod and stick to bring the reinforced sides of the screen up tight against the window casing. 90

7. A window screen consisting of an oblong board, a roller mounted on the bottom of the board, a roller screen mounted on a front face of the board and passing downward between the bottom of the board and the roller and screw eyes for securing the board in place above a window and allowing it together with the roller and roller screen mounted on the board to be instantly removed from the window casing. 95

8. A window screening device consisting of a portable board, means for securing the board in place above a window, a roller mounted on the lower side of the board, a curtain roller mounted on the upper front face of the board, a screen carried by the 100

roller and adapted to pass downward around the lower roller to be held by the roller against the front upper side of a window casing, a window shade mounted on the board beneath the screen curtain roller and forward of the screen, and means carried by the screen for holding it tight in place against the sides and bottom edge of the

window casing, substantially as shown and described.

In testimony whereof I affix my signature in presence of two witnesses.

HORATIO N. H. LUGRIN.
